UNITED STATES PATENT OFFICE

2,416,498

COLLECTOR RING AND BRUSH ASSEMBLY

William Ruddock, South Pasadena, Calif., assignor, by direct and mesne assignments, to The McCaffrey Ruddock Tagline Corporation, Los Angeles, Calif., a corporation of California

Application August 29, 1942, Serial No. 456,593

5 Claims. (Cl. 173—324)

1

This invention relates to slip rings and brush assemblies, and more particularly to those employed in reels of the type disclosed in my application Serial Number 383,968, for Tagline device, filed March 18, 1941, of which this application is a continuation in part, and which has matured into Patent No. 2,303,002, bearing date of November 24, 1942.

Lifting magnets, as utilized in the movement of magnetic materials are commonly attached to a derrick or other lifting mechanism, and are supplied with current through a long flexible cable. Lifting is of course controlled by opening and closing the magnetic circuit. When a reel is used for winding up the electrical cable it is necessary to provide some means for connecting the cable to a source of current supply. In my co-pending application I showed a pair of slip rings for connecting a cable on the magnet to a source of current supply. I have found that the ordinary slip ring employing a single brush is severely limited in its application.

The primary reason for the unsatisfactory operation of slip rings and brushes in a structure of this type is the fact that the tagline structure is ordinarily supported on the boom of the derrick. The shocks and jars to which the boom is subjected by the lifting and dropping of the load, by sudden stopping of the load in downward movement, by the striking of the magnet on the load, and other rough treatment causes the boom to vibrate. This vibration causes the brushes to leave the slip rings and arcing results which pits the brushes and the slip rings. In fact, if the magnet is permitted to drop freely while it is loaded and is suddenly brought to a halt by the application of the brake, the brushes can leave the slip rings for a sufficient length of time to cause the magnet to drop its load, which also violently agitates the boom and causes further sparking or arcing at the slip ring. The slip ring and brushes thus lose their efficiency and the pits resulting from the sparking tend to aggravate this condition until the slip ring is so badly pitted that it will not effectively carry sufficient current to the brushes. It can be seen that such a situation is extremely dangerous and the operator can not then be sure that the magnet will continue to support the load until he shuts off the current.

With the above disadvantages and difficulties in mind, it is an object of the present invention to provide a slip ring and brush mechanism for use in a structure which is subject to shocks and jars and violent movement, and will not be affected by such shocks and jars.

2

It is a further object of the present invention to provide a slip ring mechanism which is equally effective in all positions.

This invention possesses many other advantages and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of the invention is best defined by the appended claims.

Referring now to the drawings:

Figure 1 is a general side view of the device involving the present invention installed on a crane;

Figure 2 is an enlarged fragmentary sectional view taken on line 2—2 of Figure 1;

Figure 3 is a still further enlarged section of part of the structure shown in Figure 2; and

Figure 4 is a section taken on line 4—4 of Figure 2.

In Figure 1 there is shown a derrick or crane having a boom 10, and supporting a lifting magnet 11. In order to prevent the hoisting lines 12 from crossing, and also to preserve the cable from mechanical harm, a tagline 13 is secured to the magnet 11 and is wound upon a reel 14. This reel 14, in addition to keeping the tagline 13 taut, also serves to wind the magnet cable 15. The magnet 11 is thus kept from spinning and the cable 15 is protected from undue tension and is prevented from dragging upon the ground.

The reel 14 is spring driven, as was fully explained in my co-pending application, Serial Number 383,968. The particular spring drive employed forms no part of the present invention, and for the present it is sufficient that the spring housing 16 be considered as secured to the boom by means of clamps 17. The reel 14 is rotatably mounted on this housing by means of a shaft 18. A flanged hub 19 mounted on the shaft 18 carries the reels and the collector rings. An insulated stud 20 passing through the flange 21 and a similar stud 22 passing through another portion of the flange are threaded into the collector rings 23 and 24 respectively. These studs thus form electrical terminals by which the ends of the magnet cable 15 are attached to the collector rings. The collector rings 23 and 24 are insulated from each other and from the rest of

the structure by an interior tube 25 and discs 26 and 27 formed of insulating material.

A cover 28 is secured to the spring housing 16 by bolts 28a, and serves to protect the collector rings and brushes from dirt and mechanical damage. Mounted on this cover 28 is a bolt 29 which serves as a support for the brush holders. As can be seen by referring to Figures 3 and 4, each collector ring engages a pair of brushes 30 and 31, which are electrically connected together and thus form in effect a single brush. However, they are supported on arms 32 and 33 respectively, which are pivoted together on the bolt 29 and are mechanically freely movable with respect to each other. A spring 34 furnishes the necessary pressure to hold the brushes on the slip ring. As can be seen, this spring is simply a generally rectangular loop of wire with eyes 34a formed in its longer sides to pass around the bolt 29, the short sides of the rectangle engaging the outer periphery of the brush holder arms and tending to force them toward each other. Both sets of brushes are identical so far as mechanical structure is concerned and the set of brushes on the slip ring 33 will not be further described.

It can be seen from the drawing that the bolt 29 is fastened to the boom so that a line drawn through the center of the shaft 18 and parallel to the axis of the boom passes through the bolt 29. This being so, the centers of the arcs of contact of the brushes fall on a line perpendicular to the axis of the boom. It will be understood that the line passing through the centers of the arcs of contact of the brushes need not be absolutely perpendicular to the axis of the boom, but the angle between this line and the axis of the boom should be a substantial one for the best results.

When a load is dropped, or when the device is so operated that a sudden strain is placed on the load carrying magnet, e. g., if the brake is suddenly applied during downward movement of the magnet, very violent oscillations are set up in the boom. Such oscillation results in acceleration of the boom in the directions indicated by the full and dotted arrows of Figure 4. A downward acceleration of the boom will cause the brush 30 to tend to leave the collector ring. The same acceleration, however, will tend to press the brush 31 more firmly against the collector ring. In addition to this, if the brush 30 actually leaves the collector ring, it will flex the spring 34 in such a manner as to more tightly press the brush 31 against the collector ring. If the acceleration is in an upward direction it is the lower brush 31 which tends to leave the collector ring and the upper brush 30 which is more tightly pressed against the ring.

The low resistance in the short lead 40 connecting the two brushes of each pair assures that if one brush of a pair leaves the collector ring there will be no arcing, as one brush is sufficient to carry the entire magnetizing current. In actual practice it has been found that the use of a pair of brushes arranged in the fashion described eliminates entirely arcing between the brushes and the ring, and the load is never dropped because of the opening of the circuit at the brushes.

I claim:

1. In a conductor and brush assembly adapted for use on a structure having a principal plane of vibration a support; a rotary conducting mem-

ber, a pair of brushes, means pivotally supporting said brushes on said support for independent movement toward and away from said member in substantially opposite directions substantially parallel with an element of said plane extending in the direction in which said vibration acts whereby said brushes are adapted to clasp said member by engaging areas on substantially opposite sides thereof, and resilient means mounted independently of said support and connected between said brushes for simultaneously urging them toward said member.

15 2. A conductor and brush assembly adapted for use on a structure having a principal plane of vibration, comprising a member providing a curved conducting surface rotatable about an axis substantially normal to an element of said plane extending in the direction of said vibration, a pair of brushes adapted to contact respectively 20 areas on said surface adjacent the opposite ends of a diameter of said surface, means forming a common pivotal support for said brushes, whereby said brushes are independently movable toward and away from said conducting surface in 25 a plane parallel with said element, and resilient means connecting said brushes for simultaneously urging them toward said surface.

3. A collector and brush assembly comprising, 30 a support, a member adjacent said support having a cylindrical conducting surface, said support and said member being subject to sudden relative vibratory movement along a line substantially perpendicular to the axis of said member, a brush holder having a pair of arms disposed one on each 35 side of the cylindrical surface of said member, a pair of brushes mounted respectively on said arms and engaging the cylindrical surface of said member at points on said line substantially diametrically opposed with respect to said cylinder, means movably mounting said holder on said support effective to permit movement of said brushes with respect to said support substantially along said line, and means effective to bias said brushes 40 against the cylindrical surface of said member.

4. A collector and brush assembly comprising, 45 a support, a member adjacent said support, said support and said member being subject to sudden relative vibratory movement along a line substantially perpendicular to the axis of said member, a brush holder having a pair of arms disposed one on each side of said member, a pair of brushes mounted respectively on said arms and engaging said member at points on said line substantially diametrically opposed with respect to said cylinder, means pivotally mounting said holder on said support spaced appreciably away from said member and effective to permit movement of said brushes with respect to said support substantially along said line, and means effective to bias said brushes toward said member.

5. A collector and brush assembly comprising; 50 a support; a member adjacent said support; said support and said member being subject to sudden relative vibratory movement along a line substantially perpendicular to the axis of said member; a brush holder having a pair of arms disposed one on each side of said member; a pair of brushes mounted respectively on said arms and engaging said member at points on said line substantially diametrically opposed with respect to said member; means mounting said holder on said support pivotally about an axis parallel to the axis of said 55 member and spaced appreciably away from said

member, and effective to permit movement of said brushes with respect to said support substantially along said line; and means effective to bias said brushes toward said member.
